UNITED STATES PATENT OFFICE.

BERNARD H. BLANK, OF NEW YORK, N. Y.

DESIGN FOR A CLAMP FOR EYEGLASSES OR SIMILAR ARTICLES.

SPECIFICATION forming part of Design No. 33,355, dated October 16, 1900.

Application filed September 14, 1900. Serial No. 30,078. Term of patent 14 years.

To all whom it may concern:

Be it known that I, BERNARD H. BLANK, a citizen of the United States, residing at the city of New York, county of New York, in the State of New York, have invented and produced a new and original Design for a Clamp for Eyeglasses, &c., of which the following is a specification.

My invention relates to a new and original design for an article of manufacture—namely, a clamp for eyeglasses or similar articles; and it consists in the shape or configuration of the same, substantially as shown in the accompanying drawings, in which—

Figure 1 is a perspective view. Fig. 2 is an end elevation; and Fig. 3 is a sectional elevation on the line 3 3, Fig. 2.

At 1 is the lens-clamp, having apertured eyes 2, and at which eyes terminate the converging arms 3 3^a. In the opposite end of said arms is the circular portion 4, which is vertically disposed between the two sets of arms 3 3^a. From the center of the circular portion 4 projects the round pillar 5, having

a longitudinally-threaded aperture partially 25 through its center. On the opposite end of the pillar 5 is the square-shaped nose-box 6, having a transverse vertical wall 7 and outwardly-extending sides 8 and 9.

It will be noticed that there are six arms 30 3 3^a, formed in sets of three in spoke-like form, extending or converging from the eyes 2, and a space 10, formed between both sets of arms. From the point of intersection of the curved part 4 and the outer arms 3 extend 35 pointed lugs 11, curved to correspond with part 4.

Having described my invention, I claim—

The design for a clamp for eyeglasses, or similar articles substantially as herein shown 40 and described.

Signed at the city of New York, county of New York, and State of New York, this 12th day of September, 1900.

BERNARD H. BLANK.
